GUSTAV KÖHLER, OF MULHEIM-RUHR, GERMANY, ASSIGNOR TO SIEMENS-SCHUCKERT-WERKE AKTIENGESELLSCHAFT, OF BERLIN-SIEMENSSTADT, GERMANY, A CORPORATION OF GERMANY

BLADES FOR TURBINE ROTORS

Application filed January 18, 1930, Serial No. 421,721, and in Germany December 29, 1928.

My invention relates to improvements in blades for turbine rotors and the method of their manufacture.

The thick bead, flange or broadened edge 5 at the periphery of the largest diameter disk of the turbine rotor, necessary for the now generally employed blades, which are inserted at the periphery in radial direction, and to which the steam is admitted in axial direction, strictly limits the attainable output of 10 the turbine owing to the great centrifugal stresses set up in the disk by the bead. Attempts have therefore been made either to reduce the thickness of this beading or to 15 remove it entirely, which can be accomplished by inserting the blades into the rim in the direction of the disk axis, instead of inserting them in radial direction.

Quite a number of different forms of blade 20 bases, insertable into the wheel rim in the direction of the wheel axis, have been suggested in the prior art. Notwithstanding the great advantage accruing to this mode of blade attachment by way of a decrease in the 25 centrifugal stresses in the disk periphery, and thus the possibility of increasing the peripheral speed, this construction, so far as I am aware, has not been favored by turbine manufacturers up to the present.

30 The reason becomes obvious when one considers that in this type of construction it had always been proposed to provide the disk at its periphery with slots opening into axially directed cylindrical recesses. The blades 35 corresponding to the shape of the slots are provided with thin stems or shanks, each stem terminating at the inner end in a cylindrical base to fit the cylindrical recess in the disk. In this proposed form the blade has a considerably thicker portion toward its outer end, 40 and right above the stem, a considerable thickness, necessary for imparting to the blade itself the proper rigidity to withstand the impelling stresses of the driving medium.

45 Those skilled in the art of mechanics will appreciate at once that a machine element of such abrupt changes in the cross-sectional areas is quite unsuitable for the great stresses developing in modern turbines.

50 My invention while making use of the

meritorious idea of inserting the blades in axial direction, does away at the same time with the thickened disk rim, and also eliminates the defects which up to the present have adversely affected the general introduction of this type of blading into practical turbine construction. According to my invention the blades have a wedge-shaped base, the load supporting cross-sectional area of which progressively decreases from the extreme end portion of the base toward the beginning of the blade proper, where it emerges from the disk periphery. A form of blade is thus obtained which has a cross-section conforming with the shape requirements for 60 withstanding the great stresses developing in modern turbines, and being free from any sudden changes in cross-sectional area, undercuts, notches, thickened portions or beads, such as are present in the prior art suggestions of axially inserted blade bases, with 65 their incident internal stresses and the stresses upon the material at the disk periphery.

The beneficial results obtained by the blade 75 base form of continuously increasing thickness according to the present invention are of particular importance for the low pressure blading of steam turbines.

It would appear from contemporary art 80 and publications that the limit has been reached regarding the size of the low pressure wheels and blades for a given speed, and that the present day steam turbine design has reached the upper limit of the "critical output" 85 which latter is the maximum output which can be obtained from any kind of turbine at a given speed.

Since the first turbines were constructed, this critical output has been gradually 90 raised. At present, so far as I am aware, for instance not more than 85,000 k. w. can be developed by a turbine running at 3,000 R. P. M. From the foregoing it will be obvious that this value is determined by the 95 blade and disk stresses occurring in the last low pressure wheel. It would thus seem that the critical output of a turbine set could be further raised only by an extensive subdivision of the low pressure stage, or by em- 100

ploying steam abstraction or bleeding, to relieve the low pressure stage. All these remedies involve, however, considerable costs and are at best only emergency solutions of the problem, because they do not touch the real essence of the problem, i. e. the reduction of the mechanical stresses.

Therefore, if great accumulations of material at the circumference of the disk, present in modern turbines can be removed without adversely affecting the strength of the blades as proposed by my present invention, it becomes possible to considerably raise the critical output. Such blades have the most favorable design if, according to my invention, the boundary surfaces of the blade base located in the wheel rim and the adjoining portions of the blade, which face in the direction of the wheel plane, have the contour, or 20 constitute portions of the contour, of symmetrical bodies produced by rotation, more particularly conical surfaces, which possess a common axis.

Blades constructed on this principle establish, as calculations have shown, extremely favorable conditions as regards strength when moving at high peripheral wheel speeds, and permit of a substantial raising of the capacity limit of a turbine, having 30 such rotor blade construction.

I will now describe my new and improved form of blading with conical blade bases and the mode of its manufacture with reference to the examples illustrated in the accompanying drawings, in which

Fig. 1 represents the face view of a portion of the disk periphery with the blade bases inserted into the slots, the blades being indicated in transverse section taken at a 40 distance from the base,

Figs. 2 and 3 represent transverse sections of the disk rim with a portion of a blade, these figures showing different modes of locking the blade bases to the rim,

Fig. 4 shows in a developed face view of the disk periphery a further modification of securing the blades on the disk.

Fig. 5 represents a section of a multi-disk rotor portion, showing the relative position 50 between the rotor and stator blades, and

Fig. 6 represents in side elevation a portion of the disk rim with the blades in place.

One embodiment of my invention is illustrated in Fig. 1 of the drawings which shows 55 a portion of the wheel periphery face with several blades inserted into their respective slots, the blades themselves appearing in transverse section, on about the line $d-d$ in Fig. 6. The slot for the blade is designed as a portion of a conical ring more clearly shown at C in Fig. 6, with the common axis m for the radius r_1 for the inner boundary surface, and the radii r_2 for the outer surface, which latter radii become larger and larger with increasing depth of the slot. In Fig. 1 radius

r_2 prevails at the intersection of the outer boundary surface with the disk periphery. The axis m is spaced from the central plane p through the disk at right angles to its axis, by the distance l . The base of the blade inserted into such a slot is milled with cutters having correspondingly similar shaped cutting surfaces. The concave face of the blade proper is milled at the radius r_1 , and its convex face at the radius r_2 , with the center m' . 70 This mode of manufacture of the blading has the advantage that drawn material may be used for the blades which requires only very little finishing work. After milling the blade profile it is only necessary to finish the edges a and b in the manner indicated. A number of complete blades assembled on the rim are shown in Fig. 6 in side elevation. From this figure the gradually increasing thickness of the base, starting from the thickness of the 80 blade at the disk periphery, toward the extreme inner end of the base can be clearly seen.

To lock the blade bases against axial displacement, the wheel disks 1 may, for instance 90 as shown in Fig. 2, be slightly undercut at a distance from the periphery, so that the bases of the blades 2 project by a small amount into this undercut position. These projecting base portions may be conveniently upset or peened over the slot edges. Another way of locking the blades in position is to provide the bases with a bore close to the wheel periphery, through which is threaded a wire 3, which rests in a central peripheral groove provided in the wheel as shown in Fig. 3 of the drawings. The slot for the blade base may also be made so that it enters at one side of the rim, but stops short of the other rim side, so that a small amount of material remains standing, 100 against which the blade is able to abut, as shown in Fig. 4 which represents a face view of a portion of the wheel rim developed into a straight plane. 4 is the outer wheel periphery, 5 are the milled slots which do not extend across the entire width of the wheel. The blades may be held in position similar to the 105 manner shown in Fig. 3.

It will be understood that the novel kind of blading is not only of special advantage for turbines composed of individual wheel disks but also for turbine constructions in which a plurality of disks are combined into a unit. In the constructions used heretofore it was necessary either to combine the individual disks into a very thick disk with correspondingly strengthened hub or, if this accumulation of material was to be avoided the disks, cut out of a blank cylinder, had to be spaced far apart to enable the intermediate material to be machined out by the turning tool. Very broad stationary guide blades are then required, however. If, on the other hand, my improved blading is made use of in which enlarged rims, or the like are omitted, the disks 110 115 120 125 130

may be machined out of a blank cylinder, with normal spacing. A construction is then obtained in which the diameter of the blade wheel may be increased far beyond the dimensions permissible now, due to the absence of large accumulations of material on the largest circumference of the disk.

In turbines equipped with my improved blading a special packing for the clearance is necessary. This packing may in very simple manner be produced by providing the disks with projections which form the counter faces for the usual packing sheets on the stationary guide blades. This construction is by way of example illustrated in Fig. 5 of the drawings. Referring to this figure, 10 are the impeller blades, 11 the stationary guide blades. The impeller blades 10 are axially inserted into the disks 12 machined out of a blank cylinder. The disks 12 are provided with small projecting annular rims 13 which may be integral with the disks and be machined out of them or may be attached by suitable means not shown here. These rims form the counter faces for the packing sheets 14 of the guide blades 11. The slots which hold the blade bases may be cut into the wheel periphery by any suitable means known in the art, such as for instance by milling, a feature which forms no part of the present invention and has therefore been omitted from the description and drawings.

I claim:

1. A turbine rotor disk having rigid blades extending radially from the disk periphery and having at least one curved medium guide surface, each blade having a solid base integral with the blade and being insertable into the disk rim in the direction of the disk axis, said base having a thickness, measured in the circumferential direction of the disk, which gradually increases from the blade thickness measured at the disk periphery, toward the extreme base end, whereby the transverse-sectional area of the base is gradually increased toward the base end in amounts to form together with the blade a structure of substantially uniform strength.

2. A turbine rotor disk having rigid blades extending radially from the disk periphery and having at least one curved medium guide surface, each blade having a solid base integral with the blade and being insertable into the disk rim in the direction of the disk axis, said base having a thickness, measured in the circumferential direction of the disk, which gradually increases from the blade thickness, measured at the disk periphery, toward the extreme base end, whereby the transverse-sectional area of the base is gradually increased toward the base end in amounts to form together with the blade a structure of substantially uniform strength, said disk having substantially axially directed slots in its periphery conforming with

the shape of the blade bases to permit the insertion of the blades into the disk in the direction of the disk axis.

3. A turbine rotor disk having radially extending axially inserted blades, each blade having a base forming on one side a continuation of one blade surface, said base, measured in the circumferential direction of the disk, having a thickness gradually increasing from the blade thickness at the disk periphery toward the extreme base end, the longitudinal sides of said base forming parts of the inner and outer surface of an annular rotary body.

4. A turbine rotor disk having radially extending axially inserted blades, each blade having a base forming on the blade side facing against the direction of rotation a continuation of the blade surface, said base, measured in the circumferential direction of the disk, having a thickness gradually increasing from the blade thickness at the disk periphery toward the extreme base end in amounts to form a blade body of substantially constant strength, the longitudinal sides of said base forming parts of the inner and outer surface of a cone-shaped ring.

5. A turbine rotor disk having radially extending axially inserted blades, each blade having a base forming on the blade side facing against the direction of rotation a continuation of the blade surface, said base, measured in the circumferential direction of the disk, having a thickness gradually increasing from the blade thickness at the disk periphery toward the extreme base end in amounts to form a blade body of substantially constant strength, the longitudinal sides of said base forming parts of the inner and outer surfaces of a cone-shaped ring, whose center of rotation is located outside of the rotor disk periphery.

In testimony whereof I affix my signature.
